UNITED STATES PATENT AND TRADEMARK OFFICE
CERTIFICATE OF CORRECTION

PATENT NO. : Des. 481,032 S
DATED : October 21, 2003
INVENTOR(S) : Matthew Sinclair

Page 1 of 1

It is certified that error appears in the above-identified patent and that said Letters Patent is hereby corrected as shown below:

Title page,

Item [57], under **DESCRIPTION**, the following should be inserted:

-- The broken line showing of the internal surfaces and the extending tabs is for illustrative purposes only and forms no part of the claimed design --.

Signed and Sealed this

Fourth Day of May, 2004

A handwritten signature in black ink, appearing to read "Jon W. Dudas", is placed on a dotted rectangular background.
